(57) **CLAIM**

The ornamental design for an applicator for dispensing self-adhesive products, as shown and described.

DESCRIPTION

FIG. 1 is a perspective view of an applicator for dispensing self-adhesive products showing our new design;

FIG. 2 is a front elevation view thereof;

FIG. 3 is a left side elevation view thereof;

FIG. 4 is a rear elevation view thereof;

FIG. 5 is a right side elevation view thereof;

FIG. 6 is a top plan view thereof; and,

FIG. 7 is a bottom plan view thereof.

The broken lines in the drawings showing illustrate the portions of the design that form no part of the claim.
